DESIGN FOR A COMBINED NAPKIN HOLDER
AND ASH TRAYClifford Ward Williams and Clyde E. Manns,
Memphis, Tenn.

Application January 23, 1946, Serial No. 125,875

Term of patent 3½ years

(Cl. D85—2)

To all whom it may concern:

Be it known that we, Clifford Ward Williams and Clyde E. Manns, citizens of the United States of America, residing in Memphis, in the county of Shelby and State of Tennessee, have invented a new, original, and ornamental Design for Combined Napkin Holder and Ash Tray, of which the following is a specification, reference being had to the accompanying drawings, forming part thereof.

Fig. 1 is a side elevational view of a combined napkin holder and ash tray showing our new design;

Fig. 2 is a top plan view, and

Fig. 3 is an end elevational view thereof.

The front and back sides of the device are substantially identical.

We claim:

The ornamental design for a combined napkin holder and ash tray, substantially as shown and described.

CLIFFORD WARD WILLIAMS.
CLYDE E. MANNS.
